UNITED STATES PATENT OFFICE.

WILLIAM E. WHITE, OF CHICAGO, ILLINOIS, ASSIGNOR TO KALMAN STEEL CO., OF CHICAGO, ILLINOIS, A CORPORATION OF DELAWARE.

CHAIR FOR CONCRETE LEVELING DEVICES.

Application filed July 31, 1922. Serial No. 578,574.

To all whom it may concern:

Be it known that I, WILLIAM E. WHITE, a citizen of the United States, and resident of Chicago, in the county of Cook and State 5 of Illinois, have invented certain new and useful Improvements in a Chair for Concrete Leveling Devices, of which the following is a specification.

My invention relates to concrete work and 10 particularly to novel apparatus adapted for use in producing level concrete floors or other plane surfaces.

While my invention relates generally to the subject identified, it includes as well, 15 certain details of the devices employed in the novel combination. For example, the wire chair employed is particularly adapted for the use described and is in addition adapted for other uses where an elevated 20 supporting device is required. The chair here illustrated, possesses many advantages in structural form particularly the advantages incident to the process of manufacture. I employ certain standard machine-made 25 wire shapes which in the process of manufacture may be differently arranged to provide varying heights and varying widths of bar seats.

In the combination here described, the 30 chairs are employed in connection with a flat metal bar which is used as a screed for establishing a certain predetermined plane, the top surface of the bars acting as the leveling surface in connection with a hand operating 35 leveling or surfacing strip. After the concrete has been leveled the bars are removed, the chairs or supports remaining imbedded in the concrete.

The invention will be more readily understood by reference to the accompanying 40 drawing, wherein

Figure 1 is a perspective view of a section of concrete with which my improved combination is associated;

Figure 2 is an enlarged perspective view 45 showing the chair and the screed bar resting thereon;

Figure 3 is a perspective view of the chair with a different seat-spacing; and

Figure 4 is a fragment of a modified form 50 of chair-foot.

In the drawings, it will be seen that the combination is intended to be associated in the relation shown in Figure 1 in which a 55 form is indicated at 10. Chairs of suitable

height are placed on the form in proper relation and metal bars 11 are placed on the chairs with the upper surfaces of the bars in the desired finished plane of the concrete which is indicated at 12. Thereafter the 60 concrete, in plastic form, is poured in place and while in that condition is leveled by means of the leveling bar 13 or any suitable straight edge which may slide along the tops of the bars 11. After the concrete has been 65 properly leveled, in order to form a plane surface, the bars 11 are removed, the chairs remaining imbedded in the concrete. After the plastic material has set, the form is removed in the usual manner.

The chairs which constitute a novel element of the invention are preferably formed entirely of wire, the upper portion being identical in all respects with the bar chairs shown in my copending application, Serial 75 No. 567,849, filed June 12, 1922.

Said upper part is composed of duplicate members, each comprising a leg 14, a post 15, and an intermediate horizontal connecting part 16. These duplicate members are arranged in opposed relation with the horizontal parts side by side in parallelism and a U-shaped member consisting of legs 17 and a horizontal part 18 is placed in a vertical plane at right angles to the vertical plane 85 of the duplicate members. The three horizontal parts 16-18, are then welded at their junction. The advantage of this construction is in that the same parts may be employed for securing different spaces between 90 the posts 15. In the construction shown in Figures 1 and 2, the posts 15 are relatively close together, the space being just sufficient to admit the quarter-inch bar 11, while in the construction of Figure 3 the posts are 95 more widely spaced and will accommodate large reinforcing bars.

The base or lower part of the chairs consists of two U-shaped members, each having legs 19, horizontal connecting members 20, and feet 21. The feet may be secured to the form by means of a staple 22 as shown in Figure 3, or the terminal portions of the wires may be bent downwardly and sharpened to form toes 23 as shown in Figure 4. In the latter case, the sharpened projections are driven into the forms when the chairs are placed.

The U-shaped members are arranged in right angularly disposed planes and the legs 17 of the upper portion of the chair are 110

welded to the horizontal parts 20 of the base. The elevation of the seat between the posts 15 is determined by the point of weld of the legs to the base and it will be seen that a 5 relatively large variation in height may be secured by the use of the same standard parts. Thus I am enabled to vary not only the height of the chair but the width of the 10 seat without the use of other than the parts shown in the drawing.

A chair such as disclosed is stable and rigid, the structural members of the chairs being so disposed as to secure the utmost 15 vertical and lateral strength for the weight of material employed. The parts may all be formed on automatic machines and this would not be possible if a chair of the same height were attempted to be constructed without employing the separate elements 20 composing the base and superstructure of the chair.

The use of the chair in combination with the leveling bars is only one of the various 25 uses to which the chair may be put, but in that combination the chair is particularly valuable; this for the reason that differences in slab thicknesses are very common and chairs which may be utilized in that combination may be easily produced without 30 varying the setting of the automatic machines in which the different parts are formed.

Obviously the construction is capable of 35 considerable modification and I do not wish to be limited except as indicated in the appended claims.

I claim:

1. In a device of the class described, the

combination of a skeleton chair composed of wire and providing a laterally defined seat 40 a rigid bar occupying said seat, the upper surface of the bar being adapted to act as a gauge, for a concrete fill, said bar being held in position by gravity and readily removable therefrom without disturbance of 45 the fill.

2. A skeleton chair composed of wire and consisting of a base and superstructure, said base being in the form of crossed U-shaped members and said superstructure being in 50 the form of similarly placed U-shaped members, the legs of the superstructure being welded to the horizontal members of the base.

3. A skeleton chair comprising in combination 55 a base and a superstructure, said base being in the form of crossed U-shaped members, said superstructure being in the form of similarly crossed U-shaped members providing a seat at the top thereof, the legs of 60 the superstructure being welded to the base, the elevation of the seat being determined by the point of weld of the two parts.

4. A chair comprising in combination a 65 bar-supporting portion consisting of duplicate members each including a leg, a post, and a horizontal connecting member, said duplicate members being placed in opposed relation and a U-shaped member placed at right angles to said associated duplicate 70 members and welded at the junction of the parts, and a base to which the described legs are welded at required elevations.

Signed at Chicago, Illinois, this 12th day of July, 1922.

WILLIAM E. WHITE.
